United States Patent

Des. 240,556
Patented July 13, 1976

240,556

LENS VIEWER

Stanley Kirk, 3619 Lynn Lane, Wantagh, N.Y. 11793

Filed Dec. 23, 1974, Ser. No. 535,204

Term of patent 3½ years

Int. Cl. D10—04; D16—05

U.S. Cl. D10—81

FIG. 1

FIG. 2

FIG. 4

FIG. 5

FIG. 3

FIG. 6

FIG. 1 is a perspective view of a lens viewer showing my new design;

FIG. 2 is a top plan view thereof;

FIG. 3 is a side elevational view thereof;

FIG. 4 is a front elevational view thereof;

FIG. 5 is a rear elevational view thereof; and

FIG. 6 is a sectional view taken along lines 6—6 of FIG. 2.

I claim:

The ornamental design for a lens viewer, substantially as shown.
